220,982

REUSEABLE ORBITAL CARRIER AEROSPACE VEHICLE

James E. Webb, Administrator of the National Aeronautics and Space Administration, with respect to an invention of Carl F. Ehrlich, Jr., Woodland Hill, Calif.

Filed Sept. 30, 1964, Ser. No. 82,077

Term of patent 14 years

Int. Cl. D12—07

U.S. Cl. D71—1

FIG. 2

FIG. 1

FIG. 3

FIG. 1 is a side view of the multistage aerospace vehicle illustrating the ornamental design of the complete vehicle consisting of the main carrier craft with the orbital craft nested on the top surface thereof;

FIG. 2 is a top view of the multistage aerospace vehicle; and

FIG. 3 is a front view of the reusable orbital carrier aerospace vehicle.

What is claimed is:

The ornamental design for a reusable orbital carrier aerospace vehicle, substantially as shown.
